GESELLSCHAFT DER MASCHINENFABRIKEN ESCHER WYSS & CO., OF ZURICH,
SWITZERLAND.

ICE-MAKING MACHINE.

1,186,136.

Specification of Letters Patent. Patented June 6, 1916.

Application filed August 24, 1914. Serial No. 858,324.

To all whom it may concern:

Be it known that I, EDUARD RÜEGGER, a citizen of the Republic of Switzerland, residing at Zurich, Switzerland, have invented new and useful Improvements in Ice-Making Machines; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

This invention relates to an ice-making machine adapted more particularly for a small output, the demand for which is of late ever increasing for use in large households, sanatoria, by doctors, etc.

According to the invention three vessels are made of such a form and fitted one within the other in such a manner that the space left between the innermost vessel containing the compressor and the intermediate vessel is adapted to serve as a condenser, and the space left between the intermediate and the outer vessel to serve as a jacket for the cooling water. The inner wall of the intermediate vessel carries helical ribs or gills which looked at in section are inclined upward toward the axis of the casing and which have perforations formed in them in proximity to the wall of the intermediate casing for the liquefied refrigerant to flow through.

A further constructional feature of apparatus embodying the invention consists in the fact that helical ribs are also arranged between the outer and the intermediate vessel, the same being preferably formed on the outer surface of the intermediate vessel.

A construction of ice-making machine according to the invention is illustrated by way of example in the accompanying drawing, which is partly in section.

1 indicates a vertically arranged shaft that drives, through a crank 2, a piston 3 working in the compressor 4.

The refrigerant (which may for instance be ethyl chlorid) is sucked through a pipe 5 into a suction chamber 6 which communicates with the compressor 4 through ports 7 and 8 in the compressor and chamber respectively. The ports 7, 7, are formed near each end of the compressor in a vertical

plane situated at one side of the longitudinal axis of the compressor while the ports 8, 8, are formed in the top of the suction chamber in a vertical plane on the opposite side of the longitudinal axis of the chamber. The compressor is pivotally mounted on trunnions 4^a and is oscillated by the revolutions of crank 2 so that ports 7 and 8 are alternately opened and closed. When the parts are in position shown in the drawings, *i. e.*, the dead center of the crank, the ports at both ends are closed. During the first quarter revolution, the piston 3 moves to the right, oscillating the cylinder of the compressor so that the ports 7 and 8 on the left gradually come into register while the port 7 on the right moves away from the corresponding port 8 and both ports on the right are consequently closed. During this movement suction takes place through the left hand ports 7 and 8 and the refrigerant, which was sucked in on the stroke of the piston to the left, is compressed in the right hand end of the compressor cylinder and forced out through the port controlled by the valve 10. During the next, or second quarter revolution, of the crank 2 the ports 7 and 8 on the left are gradually closed and those on the right brought into closer relation. During the third quarter of the revolution of the crank these operations are reversed, *i. e.*, the ports 7 and 8 on the right are brought into register and the piston 3 creates a suction on the right and compression on the left, both this suction and compression being completed during the fourth quarter of revolution the compressed refrigerant being forced out through the port of the valve 9. It is immaterial for the purposes of the invention whether the suction chamber 6 be arranged above or below the compressor 4.

The compression chamber 11 is formed by the innermost vessel 12 and the cover 13. The vessel 12 is arranged within a somewhat larger vessel 14, the space 15 between these two vessels serving as a condenser. With this object the vessel 14 is surrounded by a vessel 16 of annular section, between which and the vessel 14 is left an annular cooling water space or jacket 17. The cooling water itself enters at the bottom through a branch 18 and passes out at the top through a branch 19.

With the object of suitably guiding the

cooling water and insuring a sufficient speed of flow of such water and consequently an effectual transference of heat, ribs 20 are provided, which are preferably arranged 5 helically on the outer wall of the middle casting 14 and which in the example shown are made integral therewith. Turned in the inner periphery of the intermediate vessel 14 are helical grooves 21 in which ribs 15 or gills 22 made as hereinafter described are fitted. These ribs or gills may for instance be made from a strip of sheet copper of suitable length and of a width $a-b$ and thickness d by winding such strip of sheet 20 copper by means of suitable appliances into a helical form and so that the ribs or gills when seen in section are somewhat inclined upward toward the center line $w-w$ of the casting. By making the ribs or gills in this 25 form two great advantages are secured. The helical shape of the copper strip 22 inserted in the grooves 21 compels the refrigerant flowing in a compressed state and consequently under pressure through the passage 23 from the compression chamber 11 to flow through the space 15 left between the innermost casting 12 and the intermediate casting 14 in a long helical path till it reaches the bottom of said space 15 and is 30 free to flow off through a pipe 24. In traversing the space in question it will give off the greater part of its heat, in particular through the medium of the strip 22 constituting the gills, to the wall 14, which is 35 water-cooled externally, and thereby be liquefied. Owing to the inclined arrangement of the band 22 the liquefied portion of the refrigerant is always caused to flow toward the cooled wall 14. In order that this 40 portion of the refrigerant need not have to traverse the whole length of the long helical path the strip 22 is formed in proximity to the wall 14 with perforations 25 through which the liquefied portion of the refrigerant 45 can fall direct from the top to the bottom. In this way the upper surface of the strip 22 is kept as free of liquid as possible, thereby enabling such strip 22 to come into as direct contact as possible with the portion 50 of the refrigerant still to be liquefied and thus facilitate the withdrawal of heat from such portion of heat still in the form of vapor. The heat absorbed by the wall 14 is given off to the cooling water entering at 55 the bottom at 18 and passing off at the top at 19 in traversing the long helical path determined by the ribs 20.

As the inner peripheral surface of the middle vessel 14 is the coldest part of the 60 whole condensing chamber 15 and that owing to the inclined position of the strip 22 the already liquefied portion of the refrigerant is constrained to flow in proximity to the wall 14, this portion of the refrigerant 65 is thereby maintained cool and consequently

liquefied thus preventing any liability of such portion to reevaporate, say through taking up heat from the vaporiform portion of the refrigerant.

An ice-making machine constructed according to the invention has great advantages compared with other types of ice-making machines. The machine as a whole takes up very little space and nevertheless is most efficient in its working. The joint 70 to be made between the cover 13 and the vessel 14 is of a simple kind and can be made really fluid-tight so as to insure safety in working. Between the vessel 12 and the cover 13 no fluid-tight joint is required at 75 all. Special pipe-connections between the compression chamber 11 and the condensing chamber 15, requiring to be made fluid tight at the joints, are entirely dispensed with. The outermost vessel 16 can be readily 80 slipped off the intermediate vessel 14 and thus enable the dirt deposited by the water to be cleared out of the cooling water jacket 17.

As hereinbefore described the structural 85 arrangement of the gills 22 insures a constant precipitation or separation of the liquefied portion of the refrigerant from that which is still in the state of vapor along the whole path traversed by the refrigerant in the condenser 15.

It will be readily understood that the channels 26 might alternatively be formed in the outermost casting 16. The strip 22 constituting the gills may, as already stated, 90 be made of sheet copper and be soldered in the grooves 21 in the intermediate casting 14 and it may consist of more than one piece. Or as alternative constructions it may be thickened toward the carrying wall 14 95 and be made integral therewith, or it may be cast into such wall 14.

What I claim is:

1. An ice making machine, comprising an inner vessel constituting a compression chamber, an outer vessel, a vessel interposed between the inner and outer vessels and forming therewith an outer cooling chamber and an inner condensing chamber, a suction chamber, a compressor adapted to 110 communicate with the suction chamber and compression chamber, and a passage connecting the latter with the condensing chamber.

2. An ice making machine, comprising an inner vessel constituting a compression chamber, an outer vessel, a vessel interposed between the inner and outer vessels and forming therewith an outer cooling chamber and an inner condensing chamber, a suction 115 chamber in the compression chamber, a compressor in the latter adapted to communicate therewith and with the suction chamber, and a passage connecting the compression chamber with the condenser chamber. 120

3. An ice making machine, comprising an inner vessel constituting a compression chamber, an outer vessel, a vessel interposed between the inner and outer vessels and forming therewith an outer cooling chamber and an inner condensing chamber, helical ribs in the condensing chamber, a suction chamber, a compressor adapted to communicate with the suction chamber and compression chamber, and a passage connecting the latter with the condensing chamber. 55
4. An ice making machine, comprising an inner vessel constituting a compression chamber, an outer vessel, a vessel interposed between the inner and outer vessels and forming therewith an outer cooling chamber and an inner condensing chamber, helical ribs in the condensing chamber inclined upwardly toward the axis thereof, a suction chamber, a compressor adapted to communicate with the suction chamber and compression chamber, and a passage connecting the latter with the condensing chamber. 60
5. An ice making machine, comprising an inner vessel constituting a compression chamber, an outer vessel, a vessel interposed between the inner and outer vessels and forming therewith an outer cooling chamber and an inner condensing chamber, helical ribs in the condensing chamber inclined upwardly toward the axis thereof, said ribs having perforations in proximity to the inner wall of the intermediate vessel, a suction chamber, a compressor adapted to communicate with the suction chamber and compression chamber, and a passage connecting the latter with the condensing chamber. 65
6. An ice making machine, comprising an inner vessel constituting a compression chamber, an outer vessel, an intermediate vessel between the inner and outer vessels forming a cooling chamber between the inner wall of the outer vessel and the outer wall of the intermediate vessel and the outer wall of the intermediate vessel and forming a condensing chamber between the outer wall of the intermediate vessel and the inner wall of the outer vessel, helical ribs on the inner wall of the intermediate vessel inclined upwardly toward the axis of the latter, a suction chamber in the compression chamber, a compressor in the latter adapted to communicate therewith and with the suction chamber, and a passage connecting the compression chamber with the condenser chamber. 70
7. An ice making machine, comprising an inner vessel constituting a compression chamber, an outer vessel, an intermediate vessel between the inner and outer vessels forming a cooling chamber between the inner wall of the outer vessel and the outer wall of the intermediate vessel and forming a condensing chamber between the outer wall of the inner vessel and the inner wall of the intermediate vessel, helical ribs on the inner wall of the intermediate vessel inclined upwardly toward the axis of the latter, said ribs having perforations in proximity to the inner wall of the intermediate vessel, a suction chamber in the compression chamber, a compressor in the latter adapted to communicate therewith and with the suction chamber, and a passage connecting the compression chamber with the condenser chamber. 75
8. An ice-making machine adapted more particularly for a small output, comprising a compressor, three vessels made of such a form and fitted one within the other in such a manner that the space left between the innermost vessel containing the compressor and the intermediate vessel is adapted to serve as a condenser and the space left between the intermediate vessel and the outer vessel to serve as a cooling water jacket, a suction chamber formed within the innermost vessel, a cover, a compression chamber formed by the innermost vessel and the cover and communicating with the condenser, helical ribs provided on the inside wall of the intermediate vessel and being when looked at in section, inclined upward toward the axis of the vessel and having in proximity to the wall of the intermediate vessel perforations for the liquefied refrigerant to flow through and helical ribs arranged on the outer wall of the intermediate vessel. 80
- In testimony that I claim the foregoing as my invention, I have signed my name in presence of two subscribing witnesses.
